UNITED STATES PATENT OFFICE.

LILLIAN S. AHRENS, OF NEW YORK, N. Y.

DESIGN FOR A QUILTED DOLL.

61,384.

Specification for Design.

Patented Aug. 22, 1922.

Application filed May 27, 1922. Serial No. 2,439. Term of patent 7 years.

To all whom it may concern:

Be it known that I, LILLIAN S. AHRENS, a citizen of the United States, residing at New York, in the county and State of New York, have invented a new, original, and ornamental Design for Quilted Dolls, of which the following is a specification, reference being had to the accompanying drawing, forming part hereof.

The figure is a front elevation view of a doll showing my new design.

I claim:

The ornamental design for a quilted doll as shown.

LILLIAN S. AHRENS.
